UNITED STATES PATENT OFFICE.

WALTER A. SHARP, OF POUGHKEEPSIE, NEW YORK.

HOISTING APPARATUS.

SPECIFICATION forming part of Letters Patent No. 415,823, dated November 26, 1889.

Application filed February 9, 1889. Serial No. 299,306. (No model.)

To all whom it may concern:

Be it known that I, WALTER A. SHARP, of Poughkeepsie, in the county of Dutchess and State of New York, have invented an Improvement in Hoisting Apparatus, of which the following is a specification.

This hoisting apparatus is especially adapted to the hoistways in warehouses and other buildings in which the article to be raised is connected with a rope or chain passing over a drum or pulley and descending on the other side, so that as one end is raised the other end is lowered, or else one end of this hoisting-chain is attached to the drum.

15 My improvement is for simplifying the apparatus and lessening the weight and cost of the same, and also for facilitating the change of gearing for the purpose of increasing the speed with which the article is hoisted for 20 light articles or lessening the speed and increasing the power for heavy articles.

In the drawings, Figure 1 is a plan view, partly in section, of my improved hoisting apparatus; and Fig. 2 is a vertical section at 25 the line *xx*.

The main shaft *A* is supported in suitable boxes or bearings *2* upon the cross-frames *b*, that are over the hoistway or elevator-shaft, and at one end of the shaft *A* is a hoist-wheel 30 *c*, the edge of which is usually grooved and sometimes provided with V-shaped cleats to prevent the rope or chain *d* slipping, and this rope or chain is endless and hangs down from the upper part of the building through 35 holes in the various floors, so that either part of the rope or chain can be pulled upon to rotate the hoist-wheel *c* and shaft *A* in either one direction or the other. Upon this shaft *A* is a hoisting drum or wheel *e*, the periphery of which is either grooved, as represented, for the rope or chain *f*, that passes over such hoist-drum and hangs down through the hoistway, or such rope is coiled around the drum and one end fastened thereto, both these 40 modes of construction being well known in elevators; or a car may be suspended from one end of the rope *f* and a balancing-weight from the other end, and I apply the brake *g* around the cylindrical flange portion *3* of the drum *e*. One end of this brake-strap is fastened and the other end acted upon by the lever *h* and a rope or chain *h²* hanging down

the hoistway, by which the brake-strap is brought into action to stop the rotation of the drum *e* or to allow such drum to rotate gradually in lowering articles attached to the hoist-rope *f*. 55

The hoisting-drum *e* is confined in its position upon the shaft *A* by collars; but it is free to revolve independently of the said shaft *A*, and upon one side of the drum *e* there is a coupling-clutch *i*, and upon the shaft *A* the slide-coupling *k* and the feather or key *4*. This coupling may be of any desired character; but I prefer to make use of a coupling 65 formed as an internal gear at *i* upon the side or end of the drum *e*, and to provide upon the sliding coupling *k* teeth corresponding in number to the teeth of the internal gear-clutch *i*, so that the clutch may be connected 70 at as many places as there are teeth, and this sliding coupling *k* is acted upon by a lever *l* upon the fulcrum *5*.

Upon the shaft *A*, at the opposite side to the coupling *k*, is a gear-wheel *m*, fitted to 75 slide upon the shaft and a key *6*, and this gear-wheel is moved endwise by the lever *n*, having a forked end passing into the grooved hub upon the gear-wheel, and this lever *n* is preferably upon the fulcrum *5* and the two 80 levers may be connected by a screw-bolt *8*, so as to be moved together, or they may be moved separately, if desired. Within the cylindrical flange portion *3* of the hoisting-drum is an internal gear *o*, and there is an 85 intermediate gear *p*, the teeth of which are always in gear with the internal gear *o*, and the stud or gudgeon *10*, upon which this wheel *p* rotates, is fastened to one of the cross-frames *b'*. It is preferable to make the gear-wheel *m* of the same size and with the same 90 number of teeth as the sliding coupling *k*, so that the coupling *k* may be slipped out of engagement with the clutch *i* simultaneously with the gear-wheel *m*, meshing into the teeth 95 of the intermediate gear-wheel *p*, and the parts are to be so placed that the sliding coupling *k* does not separate from the clutch *i* until after the teeth of *m* mesh with the teeth of the wheel *p*, so that the hoisting-drum 100 is never disconnected from the shaft *A*, and it will be apparent that when the coupling *k* is within the clutch *i* the drum *e* will be rotated at the same speed as the shaft *A*, and

the hoist-rope *f* will receive its most rapid movement; but when the article to be raised is heavier the levers *l* and *n* are moved by hand or by a suitable connection extending 5 down the hoisting-way, so as to separate the coupling *k* from the clutch *i* and simultaneously connect the wheel *m* with the gear *p*, and in this position the shaft A will be revolved a greater number of times than the 10 drum *e*, the power being in proportion to the relative sizes of the internal gear *o* and gear-wheel *m*.

The apparatus thus far described is very 15 simple and compact and only one shaft is made use of in obtaining the two speeds and proportionate power, and this apparatus, under most circumstances, will be all that is necessary for ordinary hoisting-ways; but occasionally very heavy articles require to be 20 raised, and to meet this emergency I provide a second shaft Q in boxes 12 upon the cross-frames *b* *b'*, and upon one end of this shaft Q is a small pinion *r*, and upon the other end a large gear-wheel *s*, and upon the shaft A is 25 a pinion *t*. This shaft Q can be slipped endwise within the bearings 12 and held by the collar and clamp-screw 14 against one of the bearings in either position to which it may be moved. In Fig. 1 the full lines represent 30 such shaft, pinion, and gear-wheel as out of action, and the dotted lines represent the same as in position for use, the shaft Q being slipped endwise to bring the pinion *r* into mesh with the internal gear *o* and 35 the gear *s* with the pinion *t*, and the proportion of this gearing is such that the shaft A will be revolved a large number of turns to 40 one revolution of the hoist-drum *e*, and the hoisting capacity augmented thereby correspondingly. In this case, however, it is necessary to disconnect the coupling *k* from the clutch *i* and also the wheel *m* from the intermediate gear *p*, and to do this the bolt or screw 45 8 is to be removed, so that the levers *n* and *l* can be moved independent of each other.

I claim as my invention—

1. The combination, with the main shaft A and hoisting-drum *e* upon such shaft, of the sliding coupling *k* and the sliding gear *m*, both

upon the shaft A, the levers for moving the 50 same, said drum *e* having the coupling-clutch *i* and the internal gear *o*, and the gear-wheel *p* between the movable gear *m* and the internal gear *o*, substantially as set forth.

2. The combination, with the shaft A and 55 hoist-wheel *c* and rope *d*, of the drum *e*, loose upon the shaft A, the brake-strap *g* and its actuating-rope, said drum *e* having the clutch *i* and internal gear *o*, the sliding coupling *k* and sliding gear-wheel *m* on the shaft A, the 60 intermediate wheel *p*, for connecting the gear *m* and the internal gear *o*, and the levers *h* and *n*, pivoted at 5, and a connection between the said levers, whereby the coupling *k* and gear-wheel *m* are moved simultaneously to couple the 65 drum and shaft directly together or immediately through the internal gear *o*, wheel *p*, and gear *m*, substantially as set forth.

3. The combination, with the shaft A, hoist-wheel *c*, and hoisting-drum *e*, loose upon the 70 shaft and having the internal gear, of the intermediate wheels *p* and a stationary support for the same, the gear *m*, sliding upon the main shaft, and means for moving the same out of or into gear with the intermediate gear 75 *p*, substantially as set forth.

4. The combination, with the main shaft A and hoisting-drum *e*, having the internal gear *o*, of the sliding gear-wheel *m*, and intermediate gear *p*, and the second shaft Q, pinion *r*, and 80 gear-wheel *s* upon the shaft Q, said shaft Q being within bearings, so that it may be moved endwise to connect or disconnect the gearing and the pinion *t* on shaft A, substantially as set forth.

5. The combination, with the shaft A, drum *e*, and coupling-clutch *k* *i*, for connecting the drum with the shaft or disconnecting the same, of the second shaft Q, pinion *r*, gear-wheel *s* upon the shaft Q, and internal gear *o*, 90 for applying to the drum a powerful rotation when the coupling is disconnected, and the pinion *t* on shaft A, substantially as set forth.

Signed by me this 29th day of January, 1889.

WALTER A. SHARP.
